UNITED STATES PATENT OFFICE

2,176,962

PROCESS FOR PRODUCING ETHYLENE
FROM OILJohn J. Grebe, Midland, Mich., assignor, by mesne
assignments, to Theodore Nagel, New York,
N. Y.

Application April 28, 1938, Serial No. 204,831

2 Claims. (Cl. 260—683)

This invention relates to methods for the production of unsaturated hydrocarbon gases by the pyrolysis of liquid hydrocarbons. More particularly, it is concerned with an improved process for the cracking of hydrocarbon oils to produce a fixed gas of which the major constituent is ethylene, together with a smaller proportion of other olefines containing not more than four carbon atoms per molecule.

It is an object of the present invention to produce ethylene as the principal product of an oil cracking operation in which the major portion of the charging stock is converted to fixed gases under such conditions that the yield of condensate, oil, tar, and the like, is minimized, i. e., so that not in excess of 30 per cent of condensate by weight of the charging stock, and preferably not in excess of 10 per cent condensate, is obtained. Another object of the invention is to obtain a high yield of ethylene from a preheated liquid hydrocarbon, as high as 45 per cent by weight of the stock charged, while preventing polymerization in the gases produced.

My process produces these results from liquid hydrocarbons in a continuous operation, the process comprising the operations of preheating the liquid oil under super-atmospheric pressure to a sufficiently high temperature, e. g., to a temperature slightly below its vaporizing temperature at the pressure employed although lower temperatures may be used, then injecting all of the preheated liquid oil into a hot gaseous medium, such as superheated steam, which contains sufficient heat for the heat exchange to the preheated oil to flash-heat the oil to within the temperature range of 700°—900° C. (about 1300°—1600° F.) whereby substantially all of the oil cracked is converted to ethylene and hydrocarbons containing not more than four carbon atoms per molecule, this hot gas being then immediately shockchilled to a temperature below that at which the ethylene or other olefines polymerize readily, thus substantially excluding polymerization of the olefine products.

In the annexed drawing there is illustrated diagrammatically the flow of materials in the process constituting my invention. The oil to be cracked is taken from any suitable source 1 and is forced through a preheater 2 under super-atmospheric pressure, e. g., 2 to 20 atmospheres, into a reaction chamber 3. In the pheater 2 the temperature of the oil is raised to between about 150° C. and about 500° C. (300°—950° F.), e. g., to about 450° C. (850° F.), under such conditions that substantially all the oil remains in

the liquid phase. This preheated liquid oil is continuously injected into a hotter reaction chamber 3 and flashes into vapor, the temperature of the hot reaction zone being so controlled within the range 650°—900° C. (1200°—1600° F.) that substantially all of the oil vapor cracked is converted to ethylene and other gaseous hydrocarbons containing not more than four carbon atoms per molecule.

The hot cracked gases formed in the reaction chamber 3 pass directly to a cooler 4 where they are shockchilled, preferably by means of water or a relatively cool fluid injected into said cooler, to a temperature below that at which there occurs any substantial polymerization of the olefines to form gasoline hydrocarbons, e. g., to below about 550 C. (1000° F.). In this way the yield of condensate is minimized, not more than 30 per cent of condensate by weight of the charging stock, and frequently not more than 10 per cent of condensate, being obtained. The small proportion of condensate is removed to storage 5 and the fixed gases 6 are withdrawn from the shock-cooler 4 to be treated in any known manner to separate the ethylene from other products of pyrolysis.

As hereinbefore explained, the preheated liquid oil being cracked to ethylene is at least partially flashvaporized into the hot reaction chamber 3. The source of heat in this reaction zone is a hot gaseous medium 7, e. g., a superheated condensable vapor such as steam or a hot fixed gas, for example hydrogen, carbon monoxide, etc., which is raised to the required temperature in a heater 8. This heater may take any suitable form, such as an externally heated coil or a superheater of the type described in United States Patent 2,113,536. The temperature of the hot gaseous medium flowing through the reaction chamber 3 from the vapor-heater 8 is so controlled that the gas contains sufficient heat for heat exchange to the preheated oil injected into the reaction chamber 3 to flash-heat said oil to within the desired range of reaction temperature the oil is instantaneously gasified substantially to ethylene and hydrocarbons of not more than four carbon atoms.

In practicing the invention, the liquid hydrocarbons used as the charging stock may be gas-oil and oils heavier than gas-oil, but any hydrocarbon which is liquid under pressures of up to 20 atmospheres or higher at temperatures up to 450° C. (850° F.) may be employed. It is to be understood that with different charging stocks the temperature at which the reaction takes place

and the reaction time necessary to obtain optimum yields of ethylene will vary, but in any case the reaction time should not exceed about 1½ seconds and the temperatures should not be less than about 650° C. (1200° F.) to avoid producing a larger proportion of liquid condensate. At temperatures materially above 900° C. (1625° F.) the yield of ethylene decreases, so that operation at such elevated temperatures is not desirable. The reaction time generally varies in inverse relation to the temperature, preferably ranging from approximately 1½ seconds to less than ½ second, e. g., as low as 1/50 second, in order to obtain the optimum yield of ethylene and 15 other olefines.

The following example is illustrative of the invention but is not to be construed as limiting the scope thereof:

In a continuous run a fuel oil having a specific 20 gravity of 0.877 was preheated under a pressure of 35 pounds gage to a temperature of about 220° C. (428° F.) and was injected into steam supplied at 1.5 pounds pressure and superheated to a temperature of about 1170° C. (2138° F.). 25 The oil and steam were supplied to the reaction chamber in the ratio of 3 pounds of steam per pound of fuel oil in such proportions that the average temperature in the cracking zone was about 800° C. (1472° F.) and the reaction time 30 was of the order of 0.0135 second. When operating in this manner, 9.5 cubic feet of dry fixed gas (measured at 60° F.) and 0.2 pound of condensate were obtained per pound of oil charged. The average analysis of this gas on a dry basis 35 was as follows:

Constituent:	Per cent by volume
Ethylene	39
Propylene	10
Butylene	6
Higher olefines	6
Acetylenes	6
Methane	14
Hydrogen	20
Inert gases	2
	100

Other modes of applying the principle of my

invention may be employed, change being made as regards the details disclosed, provided the step or steps stated by any of the following claims or the equivalent of such stated step or steps be employed.

I therefore particularly point out and distinctly claim as my invention:

1. The process of producing ethylene from oil, which process comprises preheating the oil under superatmospheric pressure while maintaining the oil slightly below its vaporizing temperature at that pressure, injecting all of the preheated liquid oil into a flowing superheated condensable vapor which contains sufficient heat for heat exchange to the preheated oil to flash-heat the preheated oil to within the temperature range of 1300° F. to 1600° F., at which temperature all of the hydrocarbons of the oil are instantly decomposed to ethylene and hydrocarbons of not more than four carbon atoms, and immediately upon attaining this temperature shock-cooling the gaseous mixture to below 1000° F. to exclude polymerizing reactions forming gasoline hydrocarbons and to retain the hydrocarbons as ethylene and hydrocarbon of not more than four 15 carbon atoms.

2. The process of producing ethylene from heavy oil, which process comprises preheating the oil to a temperature in the order of 850° F. while subjected to superatmospheric pressure, 20 controlling pressure and time conditions while preheating so that the oil remains in the liquid phase, injecting all of the preheated oil into a flowing superheated condensable vapor which contains sufficient heat for heat exchange to the 25 preheated oil to flash-heat the preheated oil to within the temperature range of 1300° F. to 1600° F., at which temperature all of the hydrocarbons of the oil are instantly decomposed to ethylene and hydrocarbons of not more than four 30 carbon atoms, and immediately upon attaining this temperature shock-cooling to below 1000° F. to exclude polymerizing reactions forming gasoline hydrocarbons and to retain the hydrocarbons as ethylene and hydrocarbons of not more than four 35 carbon atoms.

JOHN J. GREBE.
